J. H. PAYSON

RAZOR STROPPER

Filed March 7, 1922

John H. Payson Inventor

By

Ira J. Wilson Atty.

UNITED STATES PATENT OFFICE.

JOHN H. PAYSON, OF ROCKFORD, ILLINOIS.

RAZOR STROPPER.

Application filed March 7, 1922. Serial No. 541,761.

To all whom it may concern:

Be it known that I, JOHN H. PAYSON, a citizen of the United States, residing at Rockford, in the county of Winnebago and 5 State of Illinois, have invented certain new and useful Improvements in Razor Stropers, of which the following is a specification.

This invention pertains in general to razor 10 stropers, and has more particular reference to stropping devices particularly adapted for safety razor blades.

One of the objects of the present invention is to provide an improved razor strop 15 of this class in which the blade-holding device is carried by a handle adapted to be moved back and forth over a strop in an action simulating the stropping of an ordinary razor, and in which the position of the blade 20 is reversed at the end of each stroke and pressure of the blade against the strop is proportional to the hand pressure.

Another object is to provide a razor strop 25 of the character described constructed in a particularly novel and advantageous manner. More particularly, I have aimed to provide a razor strop having the advantages described, embodying but three main parts, namely, a blade holder, strop 30 guide frame, and a handle, and means operatively associating these parts so that they will function as desired.

Still another object is to provide a novel 35 razor blade strop constructed of such few parts that it may be produced at a comparatively low cost.

Other objects and attendant advantages will be appreciated by those skilled in this 40 art as the invention becomes better understood by reference to the following description when considered in connection with the accompanying drawings, in which—

Figure 1 is a top view of a razor blade 45 strop embodying my invention;

Fig. 2 is a longitudinal section taken on the line 2—2 of Fig. 1;

Figs. 3 and 4 are cross-sections taken substantially on the lines 3—3 and 4—4, respectively, of Fig. 1; and

Fig. 5 is a detail view of the cam member, described later.

My invention, generally stated, comprehends the provision of a blade holding device carried by a handle which may be manipulated after the fashion of stropping an ordinary razor, which device is so construct-

ed and connected with the handle that the blade will be reversed at the end of each stroke, by a slight turning movement when reversing the stroke. In the present embodiment of my invention, the handle 5 has an axial bore 6 in which is disposed a rod 7 having an upset end 8 preventing displacement of the handle in one direction and projecting at its opposite end beyond the handle for 60 the purpose of providing a support for the blade holder and the strop-guide frame. This frame 8 consists of a flat piece of sheet metal bent medially to provide sides 9 and 11 in angular relation. The rod 7 is welded or 65 otherwise fixedly secured to said frame 8 at the inside of the juncture of the sides 9 and 11. The frame 8 may, therefore, be freely oscillated about the longitudinal axis of the handle by reason of the loose mounting of 70 the rod 7 in the handle.

The blade holder proper consists of a pair of sides 12 of duplicate construction. Each side 12 has a flat blade-engaging portion 13 and a channel edge 14 adapted to embrace 80 a pivot rod 15, which in turn is pivotally mounted at its ends in brackets 16 welded or otherwise secured to the frame 8. Screws 17 are employed for clamping the blade holder sides 12 to the pivot rod 15. The 85 sides 12 being of resilient material are adapted to clamp a blade interposed between the blade holding portions 13 and it will be seen that these sides may be of any suitable shape to accommodate different razor blades. 90 The form shown is adapted for different makes of blades, particularly Gillette blades, and for this make of blade locating lugs 18 are provided. The blade holder will also accommodate those makes of blades 95 having a channel back, by reason of the separation of the blade holder sides between the portions 13 and 14. To facilitate the insertion and removal of the blades the rod 15 between the opposed channelled margins 14 of the holder sides 12 is flattened as will be evident from Fig. 3. A quarter turn of the rod from the position shown in this figure will release the tension on the blade clamping members, thus freeing the blade. It will be manifest that the blade holder may be freely oscillated about the axis of the rod 15 and that this axis is eccentric with respect to the rod 7.

Connection is now provided between the 110 blade holder and the handle, whereby said holder will be oscillated with respect to the

frame 8 at the end of each stroke. To this end, a short pin 19 is secured at one end eccentrically with respect to the rod 7 in the opposite portion 21 of a band or collar 22 embracing the adjacent end of the handle 5, and said pin 19 is loosely engaged at its opposite end in a socket 23 formed by the sides 12 of the blade holder. As a result of the foregoing construction, the blade holder 10 may be oscillated with respect to the frame 8 by oscillating the handle 5. This operation is desired for reversing the blade at each end of the stroke and such reversing action will also rock the frame 8 and present the opposite angular side to the strop for the return stroke.

In practice, referring to Fig. 3 and assuming that the line 24 represents the surface of a strop, the parts are shown in the 20 position assumed when the handle is moved to the left with a torsional pressure in a clockwise direction tending to force the blade against the surface of the strop. This pressure may be varied to suit the 25 conditions and requirements at hand. At the end of the stroke, the handle will be turned in a counter-clockwise direction, thereby swinging the blade holder about its pivot axis 15. This same movement of the 30 handle throws the opposite side 9 of the strop guide into contact with the strop, so that when the stroke is continued in the opposite direction the parts will assume a position opposite to that shown in Fig. 3. 35 The reversal of the blade holder and of the strop guide frame is instantaneous at each end of the stroke and is effected so easily that no additional effort is required, and a free and easy stropping action may be attained. It will be understood as mentioned 40 above, that the stropping pressure, that is, the pressure of the blade on the strop may be varied in direct proportion to the twist given the handle on any stroke.

45 It is believed that the foregoing conveys a clear understanding of the objects prefaced above, and while I have illustrated and described but a single working embodiment, it should be understood that changes might

be made in details of construction without departing from the spirit and scope of the invention as explained in the appended claims:

I claim:

1. A razor blade strop comprising a 55 frame having two strop engaging sides in angular relation, a handle pivotally attached to said frame at the juncture of said sides, a blade holder pivotally mounted on said frame intermediate said sides and eccentric with respect to said frame pivot, and a pivotal connection directly between said blade holder and the handle at a greater 60 radial distance from the frame pivot than said blade-holder pivot.

2. A razor blade strop comprising a 65 frame having strop-engaging sides in angular relation, a handle, a rod attached to said frame at the juncture of said sides and to the handle concentric therewith so that the frame may oscillate about the longitudinal axis of the handle, a blade holder pivotally mounted on said frame between the sides thereof and eccentric to the axis of the handle, and a pivotal connection between the handle and blade holder eccentric to said blade holder and handle axes for oscillating the blade holder by similar movement of the handle, whereby to reverse the position of the blade on the strop 70 and to similarly reverse the position of the frame on the strop.

3. A razor blade strop comprising a 75 frame having strop-engaging sides in angular relation, a handle pivotally connected to said frame to oscillate about an axis located at the juncture of said sides of the frame, a pivot rod carried by said frame between its sides and parallel to said axis, a blade holder having opposed sides fixed 80 at one end to said pivot rod and adapted at the opposite end to clamp an interposed blade, and a pivotal connection between the handle and said blade holder eccentric with respect to the pivot axis of the handle and 85 said pivot rod.

JOHN H. PAYSON.
